UNITED STATES PATENT OFFICE.

JAMES G. NOLEN, OF NEW YORK, N. Y.

TONE PROJECTOR.

Application filed December 17, 1925. Serial No. 76,013.

This invention relates to phonograph sound boxes, radio loud speakers, telephones and the like, and means for improving the quality of sound transmitted therefrom and 5 more particularly to the sound passages, through which the sound waves are conducted from the diaphragm to the horn, though it is noted that the invention is not limited to horn devices nor to mechanically or electrically vibrated diaphragms, nor in some 10 respects even to diaphragm devices.

One object of the invention is to provide a device of this kind for reproducing the upper, lower and intermediate register 15 sounds in their proper proportion.

Another object of the invention is to provide a diaphragm device of this kind in which the sound waves are transmitted from the peripheral, central and intermediate parts of the diaphragm in proper proportion to give the sounds of different register their proper value.

Another object of the invention is to adapt devices of this kind to sound boxes, 25 horns and loud speakers of different types or types already on the market.

Other objects of the invention are to improve generally the simplicity and efficiency of such devices and to provide a device 30 of this kind which is durable and reliable in operation, and very economical to manufacture.

Still other objects of the invention will 35 appear as the description proceeds; and while herein details of the invention are described and claimed, the invention is not limited to these, since many and various changes may be made without departing from the scope of the invention as claimed 40 in the broader claims.

The inventive features for the accomplishment of these and other objects are shown herein in connection with several improved diaphragm transmitters which, briefly 45 stated, include a diaphragm box comprising a top or end wall and carrying a diaphragm spaced from said wall, said wall having a sound passage, and a horn or tone arm communicating with said passage, said passage extending from the mid part of the diaphragm to the space over the periphery of the diaphragm, whereby proportionate amounts of the lower register sound waves from the periphery of the diaphragm, and

upper register sound waves from the middle of the diaphragm together with intermediate register sound waves from points between the center and circumference of the diaphragm are transmitted to said sound passage and horn, thereby to produce undistorted, natural, evenly distributed sound and prevent tumbiness from excess of sound waves from the periphery, or excess of sharpness from excess of sound waves from the mid part of the diaphragm.

In certain of the species the cross-sectional area of the sound passage is constant, while in others the sound passage tapers from the space at the diaphragm to a more restricted sound opening at the small end of 70 the tone arm or horn. In one species the sound passage is a group of passages, while in another the sound passage is formed in an adapter block for adapting the invention to loud speaking devices already known.

In the accompanying drawing, showing by way of example, several of many possible embodiments of the invention.

Fig. 1 is a side elevation, partly in section, showing the invention as applied to a phonograph diaphragm box and tone arm;

Fig. 2 is a side elevation showing the invention embodied in a loud speaking telephone;

Fig. 3 is a transverse horizontal sectional view taken on the line 3—3 of Fig. 1 looking in the direction of the arrow of said line;

Fig. 4 is a transverse horizontal sectional view, taken on the line 4—4 of Fig. 1 looking in the direction of the arrow of said line;

Fig. 5 is a transverse horizontal sectional view, partly in plan, showing a modified form of sound passage means, said section being taken on a construction similar to that of Fig. 1 at a plane corresponding to that of the line 3—3 of Fig. 1 and looking in the direction of the arrow of said line;

Fig. 6 is a side elevation, partly in axial section, showing another form of the invention embodied in a phonograph sound box;

Fig. 7 is an axial vertical sectional view, partly in elevation, showing the sound passage adapter applied to a loud speaking telephone; and

Fig. 8 is a plan showing the top of the 105 device of Fig. 7, parts being omitted.

In Figs. 1 and 2 my invention is shown embodied in a sound or diaphragm box 10

comprising a top wall 11 (Fig. 3) and an annular side wall 12 (Fig. 1) provided at the outer edge of its inner face with a laterally threaded annular groove 13 forming a shoulder 14 receiving a pair of superposed sound insulating rubber rings 15, 16 between which is disposed a diaphragm 18 spaced about one eighth of an inch below the inner face 19 of said top wall and held in place by an exteriorly threaded retaining ring 20 engaged with the threads of the groove and engaging the outer ring 16. Means including a stylus bar 21 (Fig. 1), or a telephone magnet 22 (Fig. 2) carried on a lower case member 23, vibrate the diaphragm in the usual manner.

Said top wall 11 is provided with a diametrically disposed cross-shaped sound passage 25 formed by intersecting slot arms 26 and 27 (Fig. 3); and an upstanding wall 28 surrounding said passage receives a laterally turned tone arm or horn 29 of elongated cross-section having its small end 30 (Fig. 4) of cross-shaped cross-section and mounted around said wall 28.

Certain of the slot arms 26 are quite short and terminate at the mid part of the diaphragm; while others of the slot arms 27 extend as far as to the space over the periphery 33 of the diaphragm, whereby amounts of the lower register sound waves from the periphery of the diaphragm, and upper register sound waves from the middle 34 of the diaphragm together with intermediate register sound waves from successive points 35 between the center and circumference of the diaphragm are transmitted to said sound passage and horn.

The cross-sectional areas of the various parts of the sound passages are such that the sum of the areas at the mid part of the diaphragm having about one third the diameter of the whole is about equal to the sum of the areas at the peripheral and intermediate parts 33 and 35 taken together, as this is found to produce undistorted, natural, evenly distributed sound waves and prevent tubbiness from excess of sound waves from the periphery, or excess of sharpness from excess of sound waves from the mid part of the diaphragm; though it is noted that the invention is not limited to these proportions. If the sound is found to be too sharp the peripheral and intermediate areas are increased; and if the sound is too tubby, they are decreased.

In Fig. 5 modified passage means corresponding to the cross-shaped passage 25 of Figs. 1 and 2 comprise a plurality of sound passages or bores 36 and 37 arranged in a diametrically disposed cross-shaped group formed by intersecting series or rows around which group the small end of cross-shaped cross-section of the tone arm is mounted. Certain of the rows, formed by bores 36,

terminate near the mid part of the diaphragm; while others of the rows formed by bores 37, extend to the space at the periphery of the diaphragm, just as do the slot arms of Figs. 1 and 2.

In the form of invention shown in Fig. 6, the diaphragm box comprises an end or top wall 41 having a round central sound opening 42 surrounded by a neck 43 around which the small end of the tone arm or horn 44 is received. The lower or inner part of said end or wall is spaced about one eighth inch above the diaphragm and provided with a cross-shaped sound passage 45 formed by intersecting slot arms 46 and 47, certain of the slot arms 46 terminating under the periphery of the central opening 42 at both the upper and lower faces of the end wall. Others of the slot arms 47 extend at the inner face of the end wall 41 to the space at the periphery of the diaphragm, and have inwardly and upwardly inclined upper faces 48 terminating at the periphery of the said central opening 42, whereby properly proportionate amounts of sound waves from the various parts of the diaphragm are transmitted to said central opening and horn substantially the same as in Fig. 1.

Fig. 7 shows an adapter-block 50 for conveniently applying my invention to a telephone or radio loud speaker such as are now on the market. Such a loud speaker may consist, by way of example, of a combined housing and stand 51 having a downwardly flared base forming portion 52 and a smaller interiorly threaded intermediate portion 53, a top wall 54 having a central sound opening 55 and an upstanding wall or neck 58, surrounding said opening, around which is received the small end of the upstanding laterally turned horn 59. A telephone comprising a casing having a bottom wall 60 and an annular side wall 61 having exterior threads engaged with the threads of the housing is disposed in said base and provided at its upper part with a laterally threaded inner annular groove forming a shoulder 62 receiving a pair of horizontally disposed sound insulating rubber rings 63 between which is disposed a diaphragm 64 vibrated by telephone magnets on said bottom wall just under the diaphragm. An exteriorly threaded retaining ring 65 engaged with the threads of the groove holds said rubber rings and diaphragm in place.

The disk-shaped sound passage adapter-block 50 is disposed in said housing in contact with said top wall 54 with its lower face spaced about one eighth inch above the diaphragm and is provided with a cross-shaped sound passage formed by intersecting slot arms 66 and 67 substantially as in Fig. 6, certain of the slot arms 66 terminating under the periphery of the central open-

ing at both the upper and lower face of the block, others of the slot arms 67 extending, at the lower face of the block, to the space above the periphery of the diaphragm, but 5 terminating at the upper face at the periphery of the said central opening 55, whereby inwardly and upwardly inclined upper faces 68 are formed by said slots, whereby properly proportionate amounts of sound waves 10 from the periphery and middle of the diaphragm and also from points between the center and circumference of the diaphragm are transmitted to said central opening and horn, as in Fig. 6.

15 Thus all of the species of the invention produce undistorted, natural, evenly distributed sound and prevent either tumbiness or excess of sharp sound waves.

I claim as my invention:

20 1. In combination, a means for simultaneously producing upper, lower and intermediate register sound vibrations; means forming a sound outlet; and sound passage means for conducting to said outlet the upper register vibrations and a limited amount of the intermediate and lower register vibrations.

25 2. In combination, a vibratory means for simultaneously producing upper and lower register sounds from different areas of said 30 means; means forming a sound outlet; and sound passage means for conducting to said outlet sound vibration from the upper register areas and from a limited portion of the lower register area.

35 3. In combination, a vibratory means for simultaneously producing upper, and intermediate register sounds from different areas of said means; means forming a sound outlet; and sound passage means for conducting, to said outlet, sound vibration from the upper register areas and from a limited part of the intermediate register areas.

40 4. In combination, a vibratory means for simultaneously producing lower and intermediate register sounds from different areas of said means; means forming a sound outlet; and sound passage means for conducting to said outlet sound vibration from limited parts of the intermediate and lower register areas.

45 5. In combination, a diaphragm; means forming a sound outlet; and sound passage means conducting sound to said outlet from a limited area from the mid and peripheral parts of the diaphragm, said area from the peripheral part being less than half that of the mid part.

55 6. In combination, a diaphragm; means forming a sound outlet; and sound passage means conducting sound to said outlet from a limited area from the mid and intermediate parts of the diaphragm, said area from the intermediate part being less than half that of the mid part.

65 7. In combination, a diaphragm; means

forming a sound outlet; and sound passage means conducting sound to said outlet from a limited area from the mid, peripheral, and intermediate parts of the diaphragm, said areas from the peripheral and intermediate parts being each less than half that of the mid part area.

8. In combination, an end wall having a sound outlet; and a diaphragm slightly spaced from said wall; said wall being provided with a sound passage extending from the mid, peripheral and intermediate parts of the diaphragm to said sound outlet.

9. In combination, a diaphragm box comprising an end wall; a diaphragm spaced 80 from said end wall; said wall having a sound passage; and a tone arm communicating with said passage; said passage extending from the mid part of the diaphragm to the space over the periphery of the diaphragm 85 whereby sound waves from the periphery, and from the middle of the diaphragm together with sound waves from points between the center and periphery of the diaphragm are transmitted to said sound 90 passage and arm.

10. In combination, a diaphragm box comprising a top wall and an annular side wall; a diaphragm across the box just below the inner face of said top wall; means vibrating 95 the diaphragm; said top wall having a diametrically disposed cross-shaped sound passage formed by intersecting slot arms; a horn having its small end of cross-shaped cross-section and mounted on said top wall 100 around said passage; certain of the slot arms terminating near the mid part of the diaphragm; others of the slots extending to the space over the periphery of the diaphragm.

11. In combination, a diaphragm box comprising an end wall and an annular side wall and provided at the outer edge of its inner face with a laterally threaded annular groove forming a shoulder; a pair of superposed sound insulating rubber rings resting 110 in said groove on said shoulder; a diaphragm between said rings spaced about one eighth of an inch below the inner face of said end wall; an exteriorly threaded retaining ring engaged with the threads of the 115 groove and holding said rubber rings and diaphragm in place; means for vibrating the diaphragm; said end wall having a diametrically disposed cross-shaped sound passage formed by intersecting slot arms and 120 an upstanding wall surrounding said opening; and an upstanding laterally turned horn of elongated cross-section having its small end of cross-shaped cross-section and mounted around said upstanding wall; certain 125 of the slot arms terminating near the mid part of the diaphragm; others of the slots extending to the space just over the periphery of the diaphragm.

12. In combination, a diaphragm box 130

- comprising a top wall and an annular side wall; a diaphragm across the box just below the inner face of said top wall; means vibrating the diaphragm; said top wall having a cross-shaped sound passage formed by intersecting slot arms; and a horn having its small end of cross-shaped cross-section and mounted on said top wall around said passage; certain of the slot arms being quite short and terminating near the mid part of the diaphragm; others of the slots extending to the space over the periphery of the diaphragm, whereby properly proportionate amounts of the lower register sound waves from the periphery of the diaphragm, and upper register sound waves from the middle of the diaphragm together with intermediate register sound waves from points between the center and circumference of the diaphragm are transmitted to said sound passage and horn; thereby to produce undistorted, natural, evenly distributed sound and prevent tumbiness from excess of sound waves from the periphery, or excess of sharpness from excess of sound waves from the mid part of the diaphragm.
13. In combination, a diaphragm box comprising an end wall and an annular side wall; a diaphragm across the box slightly spaced below the inner face of said top wall; means vibrating the diaphragm; said end wall having a plurality of sound passages therethrough arranged in a diametrically disposed cross-shaped group formed by intersecting series and rows of arms; a horn having its small end of cross-shaped cross-section and mounted on said end wall around said group; certain of the series of arms terminating near the mid part of the diaphragm; others of the series arms extending to the space at the periphery of the diaphragm.
14. In combination, a diaphragm box comprising a top wall and an annular side wall having a central sound opening, a diaphragm across said box; means for vibrating the diaphragm; a horn communicating with said opening; the lower part of said top wall being spaced slightly above the diaphragm and provided with a cross-shaped sound passage formed by intersecting slot arms; certain of the slot arms terminating under the periphery of the central opening at both the upper and lower faces of the block; others of the slots extending at the inner face of the top wall to the space at the periphery of the diaphragm, and having inwardly and upwardly inclined upper faces terminating at the periphery of said central opening.
15. In combination, a housing open at the bottom and having a top wall having a central sound opening; said housing being adapted to receive a telephone having a diaphragm at the upper part; and a disk shaped sound passage adapter-block disposed in said housing in contact with said top wall and having a sound passage extending from the space just above the periphery of the diaphragm to said central opening.
16. In combination, a combined housing and stand having a downwardly flared base forming portion, a smaller internally threaded intermediate portion, and a top wall having a central sound opening; a horn communicating with said opening; said housing being adapted to receive a telephone comprising a casing having an annular side wall having exterior threads engaged with the threads of the housing; a diaphragm across the upper part of the casing; and a disk shaped sound passage adapter-block disposed in said housing in contact with said top wall and having its lower face spaced slightly above the diaphragm and provided with a cross-shaped sound passage formed by intersecting slot arms; certain of the slot arms terminating under the periphery of the central opening at both the upper and lower faces of the block; others of the slots extending at the lower face of the block to the space above the periphery of the diaphragm, but terminating at said central opening.

Signed at New York, in the county of New York and State of New York, this 17th day of December A. D. 1925.

JAMES G. NOLEN.
